INTESTINE SPLITTING MACHINE

Minton S. Atkisson, Wilmette, and Arthur E. Schneider, Itasca, Ill., assignors to Armour and Company, Chicago, Ill., a corporation of Illinois

Application March 8, 1947, Serial No. 733,328

15 Claims. (Cl. 164—61)

1

This invention relates to an intestine splitting machine, and is particularly useful in the splitting of animal intestines into strips for subsequent treatment for the production of strings for musical instruments, game rackets, surgical ligatures, etc.

An object of the invention is to provide improved means for the longitudinal splitting of animal intestines whereby a more accurate division of the intestine is brought about into a plurality of parts, while at the same time forming cleaner or sharper lines of division. Yet another object is to provide new mechanism whereby the intestine is severed so as to provide strips of uniform width while avoiding the ragged edge produced by former severing devices and while effectively handling the severed portions to prevent their being drawn again into the machine. Yet another object is to provide mechanism whereby the intestines to be fed to the machine are drawn without bending upon guide members into the machine and in which the intestine is held against being picked up by the machine and injured. Other specific objects and advantages will appear as the specification proceeds.

The invention is illustrated in one specific embodiment, by the accompanying drawings, in which—

Figure 1 is a perspective view of a machine embodying our invention; Fig. 2, a transverse sectional view; Fig. 3, a detail sectional view, the section being taken as indicated at line 3—3 of Fig. 2; Fig. 4, a detail sectional view, the section being taken as indicated at line 4—4 of Fig. 2; Fig. 5, an enlarged detail sectional view, the section being taken as indicated at line 5—5 of Fig. 2; and Fig. 6, a broken perspective view showing the intestine at the point of being severed by the rotary cutting blade and the severed portions being drawn away by the take-off roller.

In the illustration given, 10 designates a base and frame for the machine. In the upper portion of the machine is rotatably mounted a knife shaft 11 and having sleeved portions 12 thereon carrying circular knives 13. Shaft 11 is provided with a universal coupling 14 and is driven by a motor 15.

Keyed upon the shaft 11 is a drive gear 16 which meshes with a large gear 17. The large gear 17 is provided with a sprocket 17a engaging the chain 18, and the chain at its other end engages the sprocket 19 on shaft 20. The shaft 20 carries a bed roll or support roll 21. The roll 21 is provided with annular recesses 22 adapted to receive the outer edges of the circular

2

cutter disk 13. On each side of the recesses 22 are supported rubber-tipped canvas members 23 adapted to aid in the gripping of the intestine and holding it in place while the severance is being accomplished by the knife 13.

The sprocket 19 may, if desired, be allowed to rotate freely upon shaft 20 and may be secured thereto by means of a clutch member 24. A key and groove 25 provide a sliding interlock between the clutch member 24 and the shaft 20.

Fixed to the shaft 20 are drive gears 26 which mesh with gears 27 mounted upon the feed shaft 28. The shaft 28 carries a plurality of feed disks. As shown more clearly in Fig. 4, the feed disks 29 and 30 may be arranged in pairs so as to receive between them the outer portion of the cutter blade 13. Each of the disks 29 and 30 is provided with a hub 31 provided with a set screw for securing it to shaft 28.

In order to support the shaft 28 effectively for its feeding function, we mount the ends of the shaft upon pivot straps 32, the straps being supported at their upper end upon the pivot pins 33 fixed to the casing 10. The straps 32 are normally urged forwardly by springs 34 which are secured to lugs upon the straps 32 at their rear end and at their forward end are secured to posts 35 carried by the cross beam 36 of the frame 10, as shown more clearly in Fig. 2. We prefer to equip the shaft 28 with a pair of gears 27, and these mesh with a pair of gears 26 fixed upon the shaft 20.

The shaft 20 is also provided with a small sprocket gear 37 engaging the sprocket chain 38. The chain 38 meshes with a sprocket carried by the take-off roll shaft 39, as shown best in Fig. 2. Mounted upon shaft 39 is a take-off roller 40 provided with spaced ribs 41. The ribs are preferably faced with rubber or other resilient strips 42. With the sprocket and chain structure shown, the take-off roller 40 is driven at a faster speed than the bed roll 21.

In order to bring the intestines to be treated from the vessel in which they are usually contained in a liquid bath, we provide horns 43, preferably formed of wire, and have the same curved downwardly and laterally, as shown best in Figs. 1 and 2. The horns extend upwardly in a somewhat vertical plane and then inwardly in a substantially horizontal plane, extending on either side of the feed disks 29 and 30 and of the knife blade 13, as illustrated more clearly in Fig. 3. The intestine 44 carried upon the horn 43 is thus held in flat relation for the severing operation, as shown best in Figs. 3 and 5.

The forward free ends of the horn 43 are preferably clamped to the cross beam 36 by means of a bar 45 through which extend threaded bolts 46.

In the illustration given, the shaft 11 is provided with a pair of cutter disks 13. It will be understood that any number of knives may be used, and any number of feeder horns 43 may be employed therewith. If desired, instead of using a single rotary knife 13 between a pair of feeder disks 29 and 30, a plurality of spaced knives may be here employed so as to sever the intestine simultaneously into a large number of longitudinal portions.

The disks 29 and 30 may be provided with any sort of surfaces which will tend to grip the surface of the intestine to feed it forwardly. In the specific illustration given, the disks 29 and 30 are formed with serrated edges 47, as shown more clearly in Figs. 2 and 4.

Operation

In the operation of the machine, power is transmitted from the motor 15 through the coupling 14 to shaft 11. Shaft 11 through its enlarged portion 12 drives the rotary blades 13. The drive gear 16 mounted on shaft 11 drives the large gear 17 and power is transmitted thence through the small sprocket 17a to the large sprocket 19 on shaft 20. Shaft 20 carries the bed roller 21 and causes the same to rotate. By means of gears 26 and the driven gears 27 on shaft 28, the feed disks 29 and 30 are rotated, and the same serve to draw the intestines forwardly toward the cutting position, as shown best in Fig. 2.

The operator feeds the intestines upon horns 43 by drawing them forwardly from the vessel below the machine containing them and until they engage the feed disks 29 and 30. Disks 29 and 30 are rotated by the suspended shaft 23 to which the gears 27 are secured.

In the feeding operation, the intestines are drawn upwardly along the spreader horns 43 and first engage the feed disks 29 and 30 and also the bed roller 21. The intestines are then automatically fed forwardly to the position where they engage the rotary knife 13. The severed portions of the intestine then fall upon the take-off roller 40 which is driven at a more rapid speed than the roller 21 and which exerts a tension upon the severed portions so that they remain in a true line relative to the cutter disk 13.

The problem of handling intestines for an accurate division thereof is difficult by reason of the natural curvature of the intestines and as a result of which one side thereof is longer than the other. Due to the natural coiled position of the intestines in the abdominal cavity and to the fact that the inner surface of the intestine has fat and tissue adhering thereto, there is an outer, longer and smooth side, and an inner, shorter and "rough" side. It is desired to separate the rough side from the longer or smooth side and this is accomplished effectively in the present machine not only because of the curvature of the horns 43 but also because of the rapidly rotating take-off roller 40 which maintains the severed portions of the intestine in accurate alignment with the blade. The rapidly rotating roller takes care of the rough and smooth severed portions of the intestine, even though one is longer than the other and prevents either from finding its way back among the rotating parts of the machine. The tension maintained upon the severed portions cooperates with the

feed rollers 29 and 30 and the bed roll 21 in maintaining the intestine always in true alignment with the rotating cutter blade 13.

In the feeding operation described, the operator does not bend the intestine at any point, but lifts it vertically upon either of the horns 43 by which it is drawn along a continuous curve into the feed mechanism of the machine.

The rubber-tipped portions 23 of the roller 21 cooperate with the feed disks 29 and 30 in providing a firm grip upon the intestine as it is drawn forward upon the horn 43 and insure uniform movement of the intestine through the machine.

The clutch 24 permits the roller or feed mechanism to be maintained idle, while the knife shaft 11 rotates. Closing of the clutch 24 to bring the teeth thereof into engagement with the clutch teeth of the sprocket gear 19 connects the sprocket 19 directly with shaft 20 and brings about the rotation of the parts as already described.

We find that the operation of the feeding disks 29 and 30 is unusually effective by reason of the support of the shaft 28 therefor upon the straps 32. The spring 34 is tensioned so as to exert the desired tension upon the intestine being fed.

The machine operates to produce longitudinal portions of intestines with clean-cut edges and in accurately-divided widths. The feed disks and the horns can be adjusted to divide the intestine in any desired widths.

While in the foregoing specification, we have set forth certain structures in great detail, it will be understood that such details may be varied widely by those skilled in the art without departing from the spirit of our invention.

We claim:

1. In apparatus of the character set forth, a frame, a guide horn for receiving an intestine, means for advancing the intestine and splitting it, a ribbed roller mounted in said frame for rotation and supported to receive the split intestine portions freely thereon, and means for rotating said roller.

2. In apparatus of the character set forth, a frame, a guide horn for receiving an intestine, rotary means for advancing the intestine, means for splitting the intestine, a rotatably-mounted roller supported for receiving freely thereon the split intestine portions, and means for rotating said roller at a faster speed than said intestine-advancing means.

3. In apparatus of the character set forth, a frame, a guide horn for receiving an intestine and directing the same forwardly, roller means for gripping said intestine while on said horn and advancing the same, means for severing said intestine as the same is advanced, a ribbed roller supported to receive freely thereon the severed intestine portions and for applying friction thereto, and means for rotating said rotary means.

4. In apparatus of the character set forth, a frame, rotary feed and cutter means mounted therein, and a guide horn adapted to receive an intestine and to guide the same toward said cutter means, said guide means having its lower portion extending downwardly in a generally vertical plane and having its upper portion inclined inwardly in a substantially horizontal plane.

5. In apparatus of the character set forth, a frame, a guide horn having a longitudinal slot

therein, a roller extending under said horn, intestine-advancing means comprising spaced disk members, a rotary cutter extending through the slot in said horn, said disk members having their peripheral portions adjacent said roller on each side of said cutter, and means for rotating said cutter.

6. In apparatus of the character set forth, a frame, a bed roll rotatably mounted therein and having a circular recess therein, a rotary cutter having its cutting edge portion received in said recess, means for guiding an intestine between said blade and recess, spaced feed disks mounted on a driven shaft with a disk on each side of said cutter for advancing said intestine toward said blade, and a driven ribbed roller on the forward side of said blade supported for receiving freely on its top surface the severed intestine portions and for drawing said intestine toward said blade.

7. In apparatus of the character set forth, a frame, a bed roll rotatably mounted in said frame and having a circular recess, rotary feed means mounted therein and including a pair of feed disks carried by a driven shaft and having their peripheral surfaces adjacent said bed roll, pivotally mounted means for supporting said shaft, a rotary cutter mounted in said frame and having its cutting edge received within said circular recess, means for guiding an intestine to said feed means and said blade, and means for rotating said driven disk and said rotary cutter.

8. In apparatus of the character set forth, a frame, a bed roll rotatably mounted in said frame and having a circular recess, rotary feed means mounted therein and including a pair of feed disks carried by a driven shaft and having their peripheral surfaces adjacent said bed roll, pivotally-mounted means for supporting said shaft, a rotary cutter mounted in said frame and having its cutting edge received within said circular recess, means for guiding an intestine to said feed means and said blade, means for rotating said driven disk and said rotary cutter, and spring means urging said driven shaft-supporting members toward said rotary cutter.

9. In apparatus of the character set forth, a frame, a bed roll rotatably mounted therein and having a circular recess therein, a rotary cutter having its cutting edge received in said recess, means for guiding an intestine between said cutter and recess, spaced feed disks supported upon a pivotally-mounted shaft, spring means urging said feed disks toward said bed roll, and means for rotating said cutter and said feed disks.

10. In apparatus of the character set forth, a frame, a bed roll rotatably mounted therein and having a circular recess therein, a resilient gripping member carried by said bed roll on each side of said recess, a rotary cutter having its cutting edge portion received in said recess, and feed disks supported above said bed roll and in alignment with said resilient gripping members.

11. In apparatus of the character set forth, a frame, a bed roll rotatably mounted therein and having a circular recess therein, a resilient grip-

ping member carried by said bed roll on each side of said recess, a rotary cutter having its cutting edge portion received in said recess, and feed disks supported above said bed roll and in alignment with said resilient gripping members, said disks being provided with serrated edges.

12. In apparatus of the character set forth, a frame, a bed roll rotatably mounted upon said frame and having a circular recess rotary feed means mounted in said frame and engaging said feed roll, means for guiding an intestine between said rotary feed means, said rotary feed means including a member having a serrated edge received within the recess of said bed roll, a rotary disk having a plain cutting edge, and means for rotating said cutting disk to sever the intestine longitudinally as it is advanced by said roller-advancing means.

13. In apparatus of the character set forth, a frame, a bed roll rotatably mounted therein and having a circular recess therein, resilient gripping means carried by said bed roll on each said side of said recess, a rotatably-mounted feed disk having its edge in contact with said resilient gripping means, a rotary cutter having its cutting edge received in said recess, and means for guiding an intestine between said blade and said recess.

14. In apparatus of the character set forth, a frame, a bed roll rotatably mounted therein and having a circular recess therein, resilient gripping means carried by said bed roll on each side of said recess, a rotary cutter having its cutting edge received in said recess, means for guiding an intestine between said blade and said recess, and spaced feed disks adjustably mounted on a driven shaft and on each side of said rotary cutter, said spaced feed disks being so positioned as to press material to be cut against said resilient gripping means.

15. In apparatus of the character set forth, a frame, a bed roll rotatably mounted therein and having a circular recess therein, resilient gripping means carried by said bed roll on each side of said recess, a rotary cutter having its cutting edge received in said recess, means for guiding an intestine between said blade and said recess, and spaced feed disks adjustably mounted on a driven shaft and on each side of said rotary cutter, said disks having teeth inclined in the direction of rotation of said disks, said disk being so positioned as to feed material to be cut against said resilient gripping means.
